UNITED STATES PATENT OFFICE

100,110

DESIGN FOR A CARTON

Byron Hassberg Lengsfield, New Orleans, La.

Application January 31, 1936, Serial No. 60,939

Term of patent 7 years

To all whom it may concern:

Be it known that I, Byron Hassberg Lengsfield, a citizen of the United States, residing at New Orleans, in the Parish of Orleans and State of Louisiana, have invented a new, original, and ornamental Design for a Carton, of which the following is a specification, reference being had to the accompanying drawing, forming part thereof in which:

Figure 1 is a rear elevation of the carton showing my new design;

Figure 2 is a plan view;

Figure 3 is a front elevation; and

Figure 4 is an end elevation.

The design, as shown, is applied to the faces of a box for packaging merchandise and the design refers to a secondary use of the box as an amusement device after the merchandise has been removed or consumed. The design suggests a theater with a curtain or screen on one side, and a stage door on the opposite side. The circular design shown in the plan view being associated with slots facilitating the insertion of a small electric light.

I claim:

The ornamental design for a carton, as described and shown.

BYRON HASSBERG LENGSFIELD.
